UNITED STATES PATENT OFFICE.

FRANK J. CLARK, OF HARMONY, MINNESOTA.

RURAL-MAIL-RECEIVING APPARATUS.

Application filed September 4, 1923. Serial No. 660,676.

This invention relates to receiving apparatus for rural mail delivery.

It is an object to provide a mail box with a rotatable receptacle for parcel post packages as well as the ordinary mail box for letters and papers and having mounted between the two a removable name plate.

It is a further object in such apparatus to make the height of the rotatable receiving apparatus adjustable.

Over twenty years of service as a rural mail carrier have well qualified the applicant to thoroughly know the conditions and needs of rural delivery and have led to this improved device for receiving mail.

To the ends above enumerated the invention consists of the novel devices and combination of devices herein described and set forth in the claims.

The invention is illustrated in the accompanying drawings wherein like notations refer to similar parts throughout the several views and, in which—

Fig. 1 is a side elevation of the device mounted in the ground;

Fig. 2 is a horizontal section taken on the line 2—2 of Fig. 1; and

Fig. 3 is a vertical section, with some portions broken away, taken on line 3—3 of Fig. 1 and looking in the direction of the arrows.

The applicant's device is supported by means of an upright post comprising cylindrical telescoping sections, the lower or stationary section of which is designated by the numeral 4 and adapted to be secured in the ground. This lower section 4 may be either of solid or hollow formation. The upper section 5 is preferably in the form of an open-ended sleeve telescoped over the stationary section 4 and having its upper end threaded. A horizontal carrying head 6, preferably of cast metal construction, has its under surface recessed at a suitable point and threaded to engage with the threaded end of the telescoping sleeve 5 and thereby rigidly connecting these parts. Although connected by threaded engagement these parts may be fastened together in any other suitable manner. The stationary section 4 is normally adapted to be seated in the recessed portion of the head 6 and thus allow the head 6 together with the sleeve 5, secured thereto, to be free for horizontal rotation thereon. The head 6 is considerably ex-

tangular seat 7 in which a standard mail box 8 may be readily secured or in which a wooden block may be fastened to accommodate a mail box of different structure. The other end of the head 6 comprises an elongated transverse securing bracket 9 herein shown of angle bar form to which a comparatively large parcel rack 10 of any suitable structure is bolted or otherwise secured. The rack 10, as herein shown, is of slatted open box formation and has side-supporting braces 11 extending from the telescoping sleeve 6 to intermediate points near the bottom of said rack. At its intermediate upper portion, preferably just above the supporting post, the head 6 has another transverse securing bracket 12 of U-shaped cross section to which an upstanding U-shaped member 13 is bolted or otherwise secured, as best shown in Fig. 3. The vertical upper sides of the member 13 are flanged to form guides for a removable name plate 14 and a horizontal lower guide 15 is fastened to the two vertical guides at the proper distance from the top of the same. The name plate 14 has a projecting portion on its upper edge, preferably of circular form, upon which the box number may be printed and which may also be used as a lifter for removing the plate. Upon the body of the name plate identification matter including the name, rural route and address of the owner is adapted to be printed in accordance with Government requirements.

As will be later explained, it is often desirable to vary the height of the receiving apparatus from the ground. To do this, the applicant provides an adjustable stop shown in the form of a clamping collar 16 which may be fastened at various suitable positions on the stationary section 4 of the post to form a seat for the lower end of the telescoping sleeve 5, thus maintaining the carrying head 6 at a desired height from the ground.

The operation of the device is probably obvious from the foregoing but may be briefly summarized as follows:

The apparatus, when installed along the road, will normally have the mail box end of the rotatable head outwardly so that, when the postman makes his delivery, the box may be readily identified from the conspicuous elevated name plate end, due to the projecting members of the rotatable head, the postman may drive up in convenient position for

5 delivery. The letters, cards, etc., may be then placed in the mail box and the head then rotated and the packages disposed in the parcel rack 10, all without the mail 10 deliverer leaving his vehicle. The rotatable head will then be turned back to its normal 15 position with the mail box outwardly.

Hitherto, much difficulty in delivering 10 parcel post packages has been experienced 15 by rural carriers since there has been no means on the regulation mail boxes for receiving parcels. As a result, the mailman 20 has often been obliged to either get out of his vehicle and set the packages at the bottom of the post or else throw them there from the vehicle with the chance of having the contents fractured. The applicant's 25 rotatable apparatus mounted on a single post will obviously overcome this difficulty. Moreover, the upstanding conspicuous name plate parallel to the road may be readily seen by the mail carrier or other passing vehicles while at present the means for identification are for the most part printed on 30 the side of the box at right angles to the road.

In the winter time when there is considerable 35 snow on the ground, the surface of the road will be much higher than usual and the ordinary rural mail box will be at a very 40 inconvenient height for the mail carrier to reach. By providing an adjustable means for maintaining the rotatable receiving apparatus at various heights, the post may be kept at the proper height at all times.

A further disadvantage of the ordinary 45 rigid boxes is that domestic animals often rub against the boxes and damage them in so doing. It is a well known fact that a 50 horse or cow will not rub against a movable object so that applicant's box will never be damaged in this manner.

From the above description, it is apparent 55 that the applicant has provided an extremely

simple and highly efficient device for receiving 60 rural mail and one which may be manufactured at a small cost. Government requirements are met in applicant's device and 65 several important advantages are obtained over the receiving apparatus in use at this 70 time.

It will, of course, be understood that various 75 changes may be made in the form, details and arrangement of the parts without departing from the scope of the invention.

What is claimed is:

1. A mounting for mail receiving apparatus comprising an oscillatory substantially horizontal head adapted to be mounted for swinging movement on a vertical axis, said head having an elongated angle seat at one side of its axis to which a parcel receptacle is adapted to be secured, and having an oppositely disposed substantially rectangular seat on the other side of its axis adapted to support a mail box and said head also having a transverse channeled portion intersecting the axis of said head to which an upstanding main plate holder is adapted to be secured. 70

2. A mounting for mail receiving apparatus comprising a substantially horizontal head, a depending pivot member secured to said head and adapted to be mounted for movement on a vertical axis, said head having a transverse elongated angle bar seat disposed at one side of its axis to which a parcel receptacle is adapted to be attached and having an oppositely disposed substantially rectangular seat at the other side of said axis being flanged to accommodate and support a standard mail box, and said head also having a transverse channeled portion intersecting said axis and disposed between said seats to which an upstanding main plate holder is adapted to be secured. 75 80 85

In testimony whereof I affix my signature.
FRANK J. CLARK.
